United States Patent Office

Des. 191,382
Patented Sept. 19, 1961

191,382

TAPE EMBOSsing TOOL

Dalny Travaglio, Berkeley, Calif., assignor to Dymo Industries, Inc., Berkeley, Calif., a corporation of California

Filed Jan. 27, 1961, Ser. No. 63,727

Term of patent 14 years

(Cl. D64—10)

FIG. 1.

FIG. 2.

FIG. 3.

FIG. 4.

FIG. 5.

FIG. 6.

FIGURE 1 is a top plan view of a tape embossing tool showing my new design;

FIGURE 2 is a left hand side elevational view thereof;

FIGURE 3 is a rear elevational view;

FIGURE 4 is a bottom plan view;

FIGURE 5 is a right hand side elevational view; and

FIGURE 6 is a front elevational view thereof.

The dominant features of the design reside in the portions shown in solid lines on the drawing.

I claim:

The ornamental design for a tape embossing tool, substantially as shown and described.
